(57) **CLAIM**

What is claimed is the ornamental design for a bracket insert, as shown and described.

DESCRIPTION

FIG. 1 is an upper perspective view of a bracket insert showing the new design;

FIG. 2 is a lower perspective view thereof;

FIG. 3 is a side view thereof;

FIG. 4 is a side view thereof;

FIG. 5 is a rear view thereof;

FIG. 6 is a front view thereof;

FIG. 7 is a top view thereof; and,

FIG. 8 is a bottom view thereof.
